The ornamental design for electronic reader for medical environments, as shown and described.

DESCRIPTION

FIG. 1 is a front perspective view of another embodiment of the electronic reader showing our new design;

FIG. 2 is a front view thereof (the rear view thereof is disclaimed);

FIG. 3 is a side view thereof;

FIG. 4 is an opposing side view;

FIG. 5 is a top end view thereof;

FIG. 6 is a bottom end view thereof; and,

FIG. 7 is a front perspective environmental view thereof illustrating the electronic reader in an exemplary medical (e.g., hospital) use environment.

The broken lines showing an example medical environment are included for the purpose of illustrating portions of the electronic reader for medical environments that form no part of the claimed design.
